UNITED STATES PATENT OFFICE

ISAAC OLSEN, OF BROOKLYN, NEW YORK

REVERSIBLE SUPERTURBINE

Application filed November 25, 1930. Serial No. 498,029.

My invention relates to rotary steam engines and refers more particularly to a super turbine which will economically utilize steam from a high to an extremely low working pressure.

One object of my invention is to provide a reversible super turbine that is simple to build and economical to run.

Another object of my invention is to provide a reversible super turbine wherein the steam pressure is utilized by applying the same in jets tangentially to the periphery of a driving wheel provided with a multiple of suitably arranged pockets.

15 A further object of my invention is to provide a reversible super turbine having a multiple of rotors of different sizes adapted to utilize high, intermediate and low pressure steam, each rotor provided with peripherally 20 arranged partitions wherein steam is injected tangentially from Y shaped jets, each yet provided with cut-off and reversing means.

A still further object of my invention is to provide a reversible super turbine, of the triple expansion impact type, with a means for instantly reversing the application of the steam pressure.

One of the most important features of my invention consists in utilizing a multiple of 30 double sleeve combined cut-off and reversing valves, wherein the cut-off valves are controlled by a multiple of cams and the reversing valves controlled by a single lever.

I attain these objects preferably by the 35 means illustrated in the accompanying drawings, wherein similar numerals refer to like parts throughout the several views, in which:—

40 Figure 1 is a partial longitudinal section of the engine.

Figure 2 is a side elevation of one of the rotors.

Figure 3 is a section taken on lines 3—3 45 of Figure 1.

Figure 4 is a section taken on lines 4—4 of Figure 1.

Figure 5 is an enlarged detail of the combined cut-off and reversing valves.

50 Figure 6 is an enlarged longitudinal sec-

tion of the double sleeve combined cut-off and reversing valve.

Figure 7 is a section taken on line 7—7 of Figure 6.

The engine is comprised of a base 1, provided with two bearings 2 and 3, split at 4 and 5, and held together by bolts like 6 and 7, and oiled by oil cups 8 and 9.

These bearings carry a shaft 10, carrying a fly wheel 11, on one end by means of the key 12, and the shaft also carries three internal cams 13, 14 and 15, by means of the key 16, and a high pressure rotor wheel 17, keyed by the key 18, to the shaft 10, an intermediate pressure rotor wheel 19 keyed to the shaft 10 by the key 20, and a low pressure rotor wheel 21, keyed to the shaft 10 by means of the key 22.

The wheel 17 is enclosed by a framework 23, formed to provide two rings 24 and 25, adapted to slidably support a multiple of cam arms, hereinafter referred to.

This casing is provided with a steam chamber 26, that is supplied high pressure steam by means of the pipe 27, and steam is fed to a multiple of Y shaped jet nozzles like 28, each nozzle being provided with a combined cut-off and reversing sleeve valve 29, which is utilized throughout the engine on the high, intermediate and low pressure wheels, which is shown in detail in Figures 1, 3, 5, 6 and 7, and will be hereinafter described in detail.

The wheels 17, 19 and 21 are all made up of the same type, differing only in the width of the partitions, each wheel having two side rings like 30 and 31, enclosing the detachable partitions 32, which are slid in slots therein, and in slots 33 in the periphery of the wheel, and these partitions are held by means of bolts like 34 and pins like 35.

The ring side 31 of the wheel 17 is provided with steam exhaust ports 36, and the wheel is preferably spoked at 37.

Steam leaves the wheel 17, through the exhaust ports 36, passes into the exhaust chamber 38, and from thence it is diverted through the passage 39, into the steam chamber 40 in the casing 41, which encloses the wheel 19, and this casing is provided with a multiple of Y jets (preferably fifteen), like 42, each

having a combined cut-off and reversing valve like 29.

The steam leaves the wheel 19, through the exhaust port 36a, passes into the exhaust chamber 48, and is directed by the passage 44 into the steam chamber 45, in the enclosing casing 46, for the wheel 21, which is provided with a multiple of Y jets, (preferably fifteen), like 47, and from this wheel the steam passes through the exhaust ports 36b, into the exhaust chamber 48, which is provided with an outlet pipe 49.

These enclosing parts 23, 41, and 46, are adapted to be bolted together with bolts like 50, and supported and held upon a support 51, on the base 1, by means of bolts like 52.

The combined cut-off and reversing valve 29 is shown in detail by Figures 6 and 7, is comprised of a base 53, recessed at 54, to provide means for holding the cut off sleeve 55, with a flange 56, which sleeve is oscillatable within the outer reversing sleeve 57, and this sleeve 55 holds the arm 58 by means of the nut 59, and washer 60.

The reversing sleeve 57 is flanged at 61, on one end and the lever 62 is attached in any suitable way to the other end, and these sleeves are sealed together by means of the washers 62a and 62b, and 62c.

The base 53 is provided with radial passages 63 and 64, which terminate against the periphery of the reversing sleeve 57, which is provided with an opening 65, adapted to register with either of these passages 63 and 64, depending upon which passage it is desirable to direct the steam into, so it is obvious that steam may be directed tangentially in opposite directions by simply moving this reversing sleeve, so that the opening 65 will register with either of these passages 63 or 64.

The cut-off sleeve 55 is provided with an opening 66, shown in the closed position in Figure 7, and it is obvious when this cut-off sleeve is moved far enough for the opening 66 to register with the opening 65, that steam will pass into the passage 63. (See Figure 7).

All of the levers 62, on the high pressure unit, are connected together by links like 67, and these links connected by the link 68 to the crank arm 69, on the shaft 70, that is provided with a handle 71, the arm on the intermediate pressure unit connected to the crank 72, and the arm on the low pressure unit connected to the crank 73, so that when the shaft 70 is reversed by the handle 71, it is possible to instantly reverse the steam throughout the whole engine.

The fifteen cut-off valves are operated by cams, five valves on each cam like 13, as shown in Figure 4, each like valve for the high, intermediate and low pressure units being connected together and operated by internal cams like 13, by means of the sliding rod like 74, with bearings in the rings 24 and 25, each of the said rods carrying rollers like 75, on one

end and a link 76 on the other end, which link is connected to a crank like 77, that is fixed in a shaft like 78, in bearings like 79 and 80, 81 and 82, and this shaft carrying crank arms 83, 84 and 85, for the high, intermediate, and low pressure units.

It is obvious that these cams 13, 14, and 15 will oscillate a group of cut-off valves through the mechanism referred to so that the steam pressure will be applied to all these wheels 17, 19 and 21, in the same manner.

In operation, when the wheels are running clockwise, the reversing valve 57, see Figures 7 and 8, is opened to the passage 63, and when the opening 66, registers with the opening 65, the steam can enter the jet passage 63 and the jet thrown upon the partition 32 and the cut off valve is so adjusted that the passages are only opened momentarily, when the partition is so positioned that the jet will hit it centrally and the impact of the steam jet imparted thereto.

Having thus illustrated and described the preferred embodiment of my invention, I do not wish to limit myself to the exact construction or arrangement of parts shown, since it is evident that modifications may be made therein, without departing from the spirit of the invention or scope of the claims.

I claim:—

1. The combination in a reversible super turbine a driving shaft rotatably carried by bearings supported on a base, said shaft carrying a pulley, cams, and wheels with peripheral partitions providing pockets therein, each wheel having enclosing sides one of said sides being provided with a multiple of exhaust ports, said wheels arranged in suitable enclosing casings provided with inlet and exhaust steam chambers, and maintained in spaced relation to each other and adapted to be impelled by the intermittent impact of a multiple of tangentially arranged Y shaped passages directing jets, of high, intermediate and low pressure steam in two opposite directions, and a combined cut-off and reversing sleeve valve, with the cut off sleeve operably connected to said cams and the said reversing sleeve operably connected to a means adapted to operate a multiple of said reversing sleeves simultaneously.

2. The combination with a reversible super turbine of a multiple of tangentially arranged duplex jets, of a multiple of combined cut off and reversing valves, having axially arranged inner and outer flanged sleeves, the inner flanged sleeves adapted to be utilized as cut-off valves and operably connected to suitable cams, the outer flanged sleeves adapted to be utilized as reversing valves and means connecting together said valves and simultaneously operating the same.

3. The combination of a reversible super turbine with a multiple of wheels carrying a

multiple of partitions and a multiple of tangentially duplex jets arranged adjacent the periphery of said wheels a multiple of valves for said jets, each provided with axially arranged inner and outer flanged sleeves, the inner flanged sleeves adapted to be utilized as cut-off valves and operably connected to suitable cams, the outer flanged sleeves adapted to be utilized as reversing valves and means connecting together said valves and simultaneously operating the same, said sleeves provided with pressure sealing means.

4. The combination of a reversible super turbine with a multiple of wheels carrying a multiple of partitions with peripherally arranged partitions providing pockets, and a multiple of tangential duplex jets, arranged adjacent to the periphery of said impellers, a multiple of valves for said jets, each having axially arranged inner and outer flanged sleeves, the inner flanged sleeves adapted to be utilized as cut-off valves, and operably connected to suitable cams, the outer flanged sleeves adapted to be utilized as reversing valves, said valves having Y shaped outlets, arranged approximately 90 degrees apart, and means connecting together said valves and simultaneously operating the same, said sleeve provided with pressure sealing means.

5. The combination with a reversible super turbine provided with a multiple of wheels, with peripherally arranged partitions providing pockets, and a multiple of tangential duplex jets arranged around the periphery of said wheels, a multiple of valves for said jets, each having axially arranged inner and outer flanged sleeves, the inner flanged sleeves having one end open adapted to be utilized as cut-off valves and operably connected to suitable cams, the outer flanges sleeves adapted to be utilized as reversing valves, said valves having Y shaped outlets arranged approximately 90 degrees apart, terminating in fan shaped outlets, and means connecting together said valves and a cam means, for independently operating the inner valves and means simultaneously operating the outer valves from a remote point, said sleeve provided with pressure sealing means.

50 Signed at New York, county of New York, State of New York, this 24th day of November, 1930.

ISAAC OLSEN.
